LOUIS GOEBBEL, OF BABYLON, NEW YORK

ORNAMENTED LINING FABRIC

Application filed January 14, 1933. Serial No. 651,742.

The present invention relates to a woven ornamented lining fabric adapted for making sectional linings for garments, each section of the lining being cut out from the fabric and having a single, identical, pre-formed and intact ornamental figure.

An object of this invention is to provide an ornamented woven lining fabric for cutting sectional garment linings having a single, identical, pre-formed and intact ornamental figure and means of identification woven therein at the lower border line of each cut section of the linings.

Another object of this invention is to provide a long strip of ornamented woven fabric for cutting sectional garment linings, the said fabric having woven therein a plurality of equally spaced identical ornamental figures positioned in a single line parallel to a selvage line, whereby a single, identical pre-formed ornamental figure is caused to remain intact at the lower border line of each cut section of the linings.

Another object of this invention is to provide a long strip of ornamented woven textile fabric for cutting sectional garment linings, the said fabric having woven therein a plurality of identical ornamental figures positioned in single line parallel to a selvage line and spaced at least eighteen inches apart, whereby a plurality of sectional garment linings, each section having a single, pre-formed ornamental mark of identification at the lower border line may be cut out in succession from any given yardage of the said fabric, the said spacing between the figures causing the figures to remain intact in all the sections of the linings.

With the above and other objects in view, the invention will be hereinafter more particularly described, and the method of manufacturing the woven ornamented lining fabric will be shown in the accompanying drawings and pointed out in the claims which form part of this specification.

Reference will now be had to the drawings, wherein like numerals of reference designate corresponding parts throughout the several views, in which:

50 Figure 1 is a perspective view of a long

strip or roll of ornamented woven fabric having woven therein a single line of identical ornamental figures so spaced and positioned as to adapt the said fabric for cutting sectional garment linings having an exclusive pre-formed and intact ornamental figure in each cut section of the lining.

55 Figure 2 is a plan view of a sectional garment lining cut from the roll of ornamented woven fabric shown in Figure 1, and shows a 60 design or arrangement of the ornamental figures.

65 Figure 3 is a plan view of a sectional garment lining cut from the roll of ornamented woven fabric shown in Figure 1, and shows 65 a different design or arrangement of the ornamental figures.

In the illustrated embodiment of the invention, the several views show an ornamented woven textile fabric 10, having woven 70 therein a plurality of ornamental figures 11, 11, which are identical in form and size and stand out in relief. The centers of all the ornamental figures 11, 11, are located in a single line 12, which is parallel and adjacent to a selvage line 13. The portion of the textile fabric 10, extending from the ornamental figures 11, to the selvage lines 14, is not provided with any ornamental figures. It will be noted that Figure 1, merely discloses a roll of 75 woven textile fabric having a plurality of ornamental figures woven therein in non-central relation. These figures do not convey the idea of the adaptability of the ornamented textile fabric for the manufacture of sectional 80 garment linings. Also, these ornamental figures are not characteristic of any portion of a completed garment lining. I have

85 found, however, that when the ornamental figures are spaced far apart to about one-third the sweep of the lining, that it is possible to cut sectional linings from the roll of fabric 10, and each lining section will have an intact pre-formed ornament and mark of identification, and that the specially spaced 90 line of ornamental figures becomes a dominant idea or motif of high utility and value 95 in the art of the manufacture of garment linings.

100 Referring to Figure 2, which shows a plan

view of a sectional garment lining 15, cut from the roll of ornamented woven fabric 10, shown in Figure 1, it will be noted that the lower border line 16, of the lining 15, has been 5 positioned adjacent to the selvage line 13, thus causing the ornamental figures 11, to be adjacent to the border line 16, and this spacing of the woven ornamental figures causes a single, identical, pre-formed ornamental figure 11, to remain intact at the lower border line in each of the front sections 17, 17, and a single figure 11, to appear in the rear section 18, of the sectional lining 15.

I have found in actual practice, that in order 15 to be able to cut out a plurality of garment linings of various sizes in succession from any given yardage of the ornamented fabric 10, that the distance between the centers of the ornamental figures 11 has to be at least eighteen inches. It is to be noted that the ornamental figures 11 are of extraordinary large size as compared with the usual run of woven ornamental figures used on textile fabrics; the ornamental figures 11 being 20 about eighteen inches in diameter, and since the spacing between centers of the figures is at least eighteen inches, the scarcity in the 25 number of figures that may be caused to appear on any lining is so pronounced and unusual as to cause the novel ornamented lining fabric heretofore described to be exclusive 30 in its field of usefulness.

Referring to Figure 3, which shows a plan view of a sectional garment lining 19, cut 35 from the roll of ornamental fabric 10, shown in Figure 1, it will be seen that the lower border line 20 of the lining 19 has been positioned adjacent to the selvage line 13 similar to that shown in Figure 2. It will also be 40 seen that the ornamental figures 11, 11, in the front sections 21, 21, are adjacent to the border line 20, and that the ornamental Figure 11 in the rear section 22 has been purposely made to appear adjacent to the upper border 45 line 23, by reversing the pattern of the said section. It will thus be noted that a roll of my ornamental fabric is not limited for the production of garment linings of one ornamental design but that quite a number of ornamental designs may be produced from one roll of fabric by manipulating the patterns of 50 the sections that make up a sectional lining.

It is to be noted that the word "sweep" is understood to mean the dimension along the 55 lower border line.

As best shown in Figure 1, more than one-half the width of the fabric 10, is not ornamented and the ornamental figures 11 are not only positioned in non-central relation on the fabric but are extraordinarily large and are 70 spaced apart about one-third the entire sweep of the lining, and this special spacing functions to produce my exclusively spaced and exclusively decorated woven fabric for making sectional garment linings, each section of 75 which has an intact identical ornamental figure positioned at will in the respective sections and irrespective of the size or shape of the lining. My new lining fabric is thus not limited to one design or arrangement of the 80 ornamental figures; it is not limited by the size or the shape of any desired sectional lining and all these three conditions are essential to be met in the production of exclusively 85 ornamented sectional linings. It is also to be noted that these exclusively spaced ornamental figures also serve as marks of identification, the same as monograms made of initial letters are attached to the lining of a garment 90 to serve as a means of identification for the garment.

Having thus described my invention, what I claim is:

1. A lining material from which sections of lining of varying sizes are to be cut, comprising a long strip of woven textile fabric provided with selvage edges and having woven therein a plurality of identical ornamental figures positioned in a line nearer to one selvage edge than the other, said figures being 95 sufficiently widely spaced apart to permit complete lining sections each including one figure to be cut in varying sizes with ample material on both sides of said figure to centrally locate the figure in said section. 100

2. A lining material from which sections of lining are to be cut, comprising a long strip of woven textile fabric having two selvage edges and having woven therein a plurality of identical ornamental figures positioned in a line parallel to and between said edges, said figures being spaced apart sufficiently to permit the largest size complete section of lining to be cut therefrom in such manner that each section includes one of said ornamental figures located centrally with respect to the cut edges of said section. 115

LOUIS GOEBBEL.
